T 19-6.

T 19-7.

FIG. 1 is a side elevation of the refractor showing my new design;

FIG. 2 is an end elevation of the refractor shown in FIG. 1;

FIG. 3 is a bottom view thereof;

FIG. 4 is a top view thereof;

FIG. 5 is an enlarged fragmentary cross-sectional view taken along the line 5—5 of FIG. 4;

FIG. 6 is an enlarged fragmentary cross-sectional view taken along the line 6—6 of FIG. 4; and

FIG. 7 is a fragmentary cross-sectional view taken along the line 7—7 of FIG. 2.

It is to be understood that the prismatic pattern shown in detail in FIGS. 5, 6 and 7 continue uniformly throughout the unshaded portions of FIGS. 1-4. The prismatic

patterns on the end and side of the fixture shown by FIGS. 5 and 6 are the same in appearance as the prismatic patterns on the undisclosed end and side thereof.

The mounting lugs shown in broken lines are for illustrative purposes only.

What I claim is:

The ornamental design for a refractor for illuminating fixtures, substantially as shown and described.
